ABSTRACT OF THE DISCLOSURE

A negative resistance circuit consists of three parallel branches. One branch consists of the collector-emitter path of a first transistor. The second branch consists of the collector-emitter path of a second transistor connected in shunt with the base-emitter path of the first transistor, with a resistor connected between the collector of the second transistor and a terminal of the circuit. The third branch consists of a resistive voltage divider connected in shunt with the collector-emitter path of the first transistor and having a tap connected to the base of the second transistor.

The invention relates to a negative-resistance circuit arrangement comprising two transistors of the same conductivity type the emitters of which are connected to each other, while the collector of one transistor is connected to the base of the other transistor. Such circuit arrangements may be used, for example, for reducing the damping in electric circuits. It is of importance that the negative resistance retains its ohmic nature in a very wide frequency range.

The invention provides a simple solution of this problem and is characterized in that the base of the first transistor is connected to a tapping on a voltage divider connected in parallel with the emitter-collector path of the other transistor, the collector of the latter transistor being connected through a resistor to its base.

The invention will now be described more fully with reference to the accompanying drawings in which:

FIG. 1 is a circuit diagram showing the basis elements of a negative-resistance circuit arrangement in accordance with the invention.

FIGS. 2 and 4 show characteristic curves illustrating the operation of a circuit of FIG. 1.

FIG. 3 shows an equivalent circuit diagram of the arrangement of FIG. 1.

FIG. 5 shows an embodiment of the invention.

The circuit arrangement shown in FIG. 1 comprises two transistors Tr_1 and Tr_2 , the collector of the first transistor being connected to the base of the second transistor. The base of transistor Tr_1 is connected to a tapping on a voltage divider constituted by resistors R_1 and R_2 and connected in parallel with the emitter-collector path of transistor Tr_2 . Furthermore, a resistor R_c is connected between the collector and the base of transistor Tr_2 . By a suitable choice of the said resistors with respect to the given characteristic curves of the transistors there is obtained between an input terminal 1 and an output terminal 2 between which a direct supply voltage is applied a current-voltage characteristic curve which, as will be proved hereinafter, includes a negative-resistance portion.

FIG. 2 represents the emitter current I_E as a function of the emitter-base voltage V_{BE} of a conventional junction transistor. It will be seen that the voltage V_{BE} must exceed a given threshold value before the emitter current starts flowing; in practice, this value may amount to a few hundreds mv. In principle, the circuit arrangement shown

in FIG. 1 comprises the parallel combination of three conductances

$$G_R = \frac{1}{R_1 + R_2}$$

5 which is constituted by the voltage divider R_1 , R_2 , $G_1 = f(V_{BE1})$, which is constituted by the series combination of the transistor Tr_1 and the resistor R_c , and finally $G_2 = f(V_{BE2})$, which is constituted by the transistor Tr_2 (see FIG. 3). When a voltage V_T is applied between the terminals 1 and 2 the said three conductances pass currents which are equal to I_R , I_{E1} and I_{E2} , respectively.

10 FIG. 4 represents as a function of the voltage V_T the overall current I_T obtainable with such a circuit arrangement. In this current characteristic curve the following sections can be distinguished. The transistors Tr_1 and Tr_2 are cut off at a value of V_T which is lower than the said threshold value. When the voltage V_T increases the emitter-base voltage of the transistor Tr_2 exceeds the threshold voltage at a given instant so that this transistor becomes conductive. Since as a result of the presence of the voltage divider R_1 , R_2 a lower voltage is applied to the base of transistor Tr_1 , this transistor does not yet become conductive at this instant. In this condition Tr_2 has a high conductivity as a result of a suitable choice of the resistors so that a very strong current I_{E2} may flow.

15 With a further increase in the overall voltage V_T finally the threshold voltage in the emitter-base path of transistor Tr_1 is also exceeded, so that this transistor becomes conductive. However, the current I_{E1} through the transistor Tr_1 produces a voltage drop across the resistor R_c , as a result of which the emitter-base voltage V_{BE2} of the transistor Tr_2 initially no longer increases and finally even decreases. The collector of transistor Tr_1 is then at a potential at which the collector-base junction of this transistor is driven in the forward direction. Consequently, the current I_{E2} through the transistor Tr_2 decreases considerably while the current through the transistor Tr_1 increases, it is true, but cannot exceed the value V_T/R_c .

20 Consequently, the overall current strongly decreases, which corresponds to the nature of a negative resistance. In the end, the conductivity of the transistor Tr_2 has decreased to an extent such that the current I_{E2} is negligible with respect to I_{E1} and I_R , whilst the currents I_{E1} and I_R still slowly increase with the voltage V_T . In this situation, 25 practically only

$$G_R = \frac{1}{R_2} \text{ and } G_1 = \frac{1}{R_c}$$

50 are significant.

In a practical embodiment use was made of transistors of the type OC 72. (The equivalent of the OC 72 is 2N281.) The resistors R_1 , R_2 and R_c were 1.2 k Ω , 10 k Ω and 560 Ω , respectively. The numerical values given in the 55 characteristic curve of FIG. 4 relate to this proportioning of the circuit arrangement. In order to obtain certain further effects it may be desirable to insert small resistors into one or both emitter leads.

FIG. 5 shows an embodiment of the invention used in 60 a trigger arrangement. The two transistors Tr_1 and Tr_2 and the resistors R_1 , R_2 and R_c are arranged in a manner similar to that shown in FIG. 1. The resulting negative resistance is connected in series with a load resistor R_L . This load resistor can be switched into circuit and out of 65 circuit in that with due regard to the correct polarity triggering pulses are applied through input terminals 3 and 4 to the bases of the transistors Tr_2 and Tr_1 , respectively. The load line corresponding to the resistor R_L is represented in FIG. 4 by a broken line; this curve has 70 two stable points of intersection 3' and 4' with the I_T - V_T characteristic curve and an intermediate point of intersection in which the arrangement is unstable. Thus, for

example, loads may be switched into circuit and out of circuit or a voltage corresponding to the state of a trigger arrangement may be taken from the output terminal 5.

What is claimed is:

1. A two terminal circuit that exhibits a negative current-voltage characteristic region between first and second positive current-voltage characteristic regions, comprising first and second terminals forming an input and output respectively, first, second and third branches connected in parallel between said first and second terminals, said first branch comprising a first transistor having its emitter connected to said first terminal, and means connecting the collector of said first transistor to said second terminal, said second branch comprising a second transistor having its emitter connected to said first terminal, and resistor means connected between the collector of said second transistor and said second terminal, said first and second transistors being of the same conductivity type, said third branch comprising a resistive voltage divider having a tap, means connecting the base of said first transistor to the collector of said second transistor, means connecting the base of said second transistor to said tap whereby said divider provides the sole direct current bias for said second transistor, a source of voltage, and means applying said voltage between said first and second terminals, whereby the voltage between said first and second terminals is variable, the resistances of said voltage divider being proportioned to hold said second transistor in a cut off state in a first range of voltage between said first and second terminals whereby only said first transistor is conductive, and to bias said second transistor to a conductive state for voltages in a second range between said terminals above said first range, whereby the collector current flow of said second transistor through said resistor means decreases the base current of said second transistor, and in a portion of said second range increasing voltages between said terminals produce a decrease in the collector current of said first transistor that is greater than the increase in collector current of said second transistor.

2. A circuit that exhibits a negative resistance characteristic between first and second terminals forming an input and output respectively, comprising first and second transistors of the same conductivity type, means connecting the emitters of said transistors to said first terminal, means connecting the collector of said first transistor directly to said second terminal, means connecting the collector of said second transistor directly to the base of said first transistor, a resistive voltage divider connected between said first and second terminals, said voltage divider having a tap connected to the base of said second transistor, and resistor means connected between the collector and emitter of said first transistor, the resistors of said divider being proportioned to hold said second transistor cut off for a first range of voltages between the emitter and collector of said first transistor at which said first transistor is conductive, and to bias said second transistor to a conductive state at a second range of voltages between the emitter and collector of said first transistor above said first range, whereby second transistor collector current increases resulting from increases in emitter-collector voltage of said first transistor are less than first transistor collector current decreases in a portion of said second range.

3. A two port circuit that exhibits a negative resistance characteristic, comprising a source of potential, a first transistor, means connecting said source between the emitter and collector of said first transistor, a second transistor of the same conductivity type as said first transistor having its collector connected directly to the base of said first transistor, means connecting the emitter of said second transistor to the emitter of said first transistor, a resistive voltage divider connected between the

emitter and collector of said first transistor, said divider having a tap connected to the base of said second transistor for providing the sole direct current bias for said second transistor, and resistor means connected between the collector and base of said second transistor, said divider being proportioned to hold said second transistor cut off for a first range of emitter-collector voltages of said first transistor during which said first transistor is conductive, and to bias said second transistor to a conductive state for a second range of emitter-collector voltages, of said first transistor above said first range, whereby a negative resistance characteristic occurs between the emitter and collector of said first transistor during a portion of said second range of emitter-collector voltages of said first transistor.

4. A circuit that exhibits a negative resistance characteristic comprising first and second terminals forming an input and output respectively, a source of potential, means applying said potential between said first and second terminals, first and second transistors of the same conductivity type, means connecting the emitter of said first transistor to said first terminal, means connecting the emitter of said second transistor to said first terminal, resistor means having one end connected to the collector of said first transistor, means connecting the other end of said resistor means to the base of said first transistor and the collector of said second transistor, whereby the only current flow through said resistor means is the base current of said first transistor and collector current of said second transistor, means connecting the collector of said first transistor to said second terminal, and a resistive voltage divider connected between said first terminal and the collector of said first transistor, said divider having a tap providing the sole direct bias for said second transistor, said divider being proportioned to hold said second transistor cut off for a first range of emitter-collector voltages of said first transistor during which said first transistor is conductive, and to bias said second transistor to a conductive state for a second range of emitter-collector voltages of said first transistor above said first range, whereby a negative resistance characteristic occurs between the emitter and collector of said first transistor during a portion of said second range of emitter-collector voltages of said first transistor.

5. A bistable circuit comprising a negative resistance circuit having first and second terminals, and a source of voltage and an output resistor serially connected between said first and second terminals, said negative resistance circuit comprising a first transistor, means connecting the emitter of said first transistor to said first terminal, means connecting the collector of said first transistor to said second terminal, a second transistor of the same conductivity type as said first transistor, means connecting the emitter of said second transistor to said first terminal, resistance means connected between the base and collector of said first transistor, means connecting the collector of said second transistor to the base of said first transistor, a resistive voltage divider connected between said first terminal and the collector of said first transistor, and a tap on said divider connected to the base of said second transistor.

6. The bistable circuit of claim 5 comprising a source of a triggering potential connected to the base of said first transistor.

7. The bistable circuit of claim 5 comprising a source of a triggering potential connected to the base of said second transistor.
